Primary Examiner — Caron D Veynar*Assistant Examiner* — Katrina A Betton(74) *Attorney, Agent, or Firm* — Foley & Lardner LLP(57) **CLAIM**

The ornamental design for an automotive charge indicator, as shown and described.

DESCRIPTION

FIG. 1 is a front perspective view of an automotive charge indicator shown on the left side of a vehicle in broken lines; FIG. 2 is a front elevational view;

FIG. 3 is a front elevational view with partial stippling representing illumination of the charge indicator;

FIG. 4 is a front elevational view with stippling representing full illumination of the charge indicator; and, FIG. 5 is a front perspective view of another embodiment thereof.

The vehicle shown in broken lines is for illustrative purposes only and forms no part of the claimed design.
